(57) **CLAIM**

The ornamental design for a “beverage bottle lid,” as shown and described.

DESCRIPTION

FIG. 1 is a top, front, and left side perspective view showing our new design for a beverage bottle lid;

FIG. 2 is a front view of the beverage bottle lid shown in FIG. 1, the rear view being a mirror image thereof;

FIG. 3 is a right side view of the beverage bottle lid shown in FIG. 1, the left side view being a mirror image thereof;

FIG. 4 is a top view of the beverage bottle lid shown in FIG. 1;

FIG. 5 is a bottom view of the beverage bottle lid shown in FIG. 1;

FIG. 6 is a top, front, and right side perspective view showing the beverage bottle lid of FIG. 1, but with alternate closure; and,

FIG. 7 is a top, front, and right side perspective view showing the beverage bottle lid of FIG. 1, but with alternate closure. The subject matter shown in dashed lines depicts environmental subject matter only and form no part of the claimed design.
